REFRIGERATING APPARATUS

Donald H. Reeves, Dayton, Ohio, assignor to General Motors Corporation, Dayton, Ohio, a corporation of Delaware

Application July 12, 1935, Serial No. 31,066

8 Claims. (Cl. 62—8)

This invention relates to refrigerating apparatus and more particularly to control means therefor.

In the cooling of beds by refrigerating systems, it is deemed undesirable to start and stop the refrigerating system in order to control the cooling of the bed. In the first place, this would provide considerable and rapid changes in the temperature within the bed and it would also be rather undesirable because it would provide intermittent periods of quiet and noise particularly the additional noise when starting and sometimes when stopping, which would tend to prevent sleep. On the other hand, if the refrigerating system is permitted to operate continuously, it will, if well made, provide a low steady hum which is not objectionable.

It is, therefore, an object of my invention to provide an improved means for controlling the temperature of a continuously operating refrigerating system and particularly one which may be readily controlled as to the temperature produced.

It is another object of my invention to provide an improved suction line control valve for a refrigerating system which will accurately meter the flow of refrigerant through the suction line according to certain temperatures.

It is still another object of my invention to provide an improved control means for a refrigerating system which employs the expansion of oil to control the temperature of the refrigerating apparatus.

Further objects and advantages of the present invention will be apparent from the following description, reference being had to the accompanying drawings, wherein a preferred form of the present invention is clearly shown.

In the drawings:

Fig. 1 is a perspective view of a bed cooler embodying my invention including a diagrammatic refrigerating air cooling system for the bed;

Fig. 2 is a sectional view of the suction line control valve of the refrigerating system shown in Fig. 1;

Fig. 3 is a fragmentary view of a portion of the oil displacement mechanism taken along the lines 3—3 of Fig. 2;

Fig. 4 shows a fragmentary portion of a domestic refrigerator provided with a refrigerating system and another form of my control means; and

Fig. 5 is an enlarged view, partly in section, of the control means shown in Fig. 4.

As the first embodiment of my invention, I have

disclosed a bed cooler having a low curtain structure extending about eighteen inches above the mattress and provided with a fabric envelope at one end into which cooled air is forced to cause the cooled air to pass slowly through the fabric wall of the envelope into the curtained enclosure. This air is supplied by an air cooler comprising a compression type refrigerating system provided with an improved form of valve in the suction line for controlling its capacity. This valve is provided with a metering needle and is operated by the liquid expansion of oil which is substantially independent of pressure. The oil which does the controlling is contained in a comparatively large metal bulb or chamber provided with an adjustable displacing means for adjusting the temperature at which the valve operates.

In the second form of my invention, I have shown a domestic electric refrigerator provided with an adjustable control switch having oil as its thermal expansible fluid. The controlling portion of this oil is contained in a comparatively large metal bulb or chamber provided with a liquid displacing means which may be used to control the temperature at which the switch operates.

Referring now to the drawings, and more particularly to Fig. 1, there is shown a bed generally designated by the reference character 20 provided with a mattress 22 and a curtained enclosure 24 extending upwardly about eighteen inches from the top of the mattress and having its lower edges tucked beneath the mattress. This curtained enclosure is provided with elastic gathered portions 26 and pockets in the hem at the four corners which are held by vertical rods or standards 28 having their bases resting upon the floor and held down by the legs of the bed. At the head end of the bed there is provided an envelope 30 having a fabric wall on its inner side. This envelope is connected by a duct 32 to an air cooling unit 34 shown diagrammatically which includes a cooling chamber 36 and a refrigerant liquefying chamber 38.

Within the refrigerant liquefying chamber 38 there is shown a compressor 40 driven by an electric motor 42 for compressing the refrigerant and for forwarding the compressed refrigerant to a condenser 44 where the compressed refrigerant is liquefied and collected in a receiver 46. From the receiver 46 the liquid refrigerant is forwarded through a supply conduit 48 to an automatic expansion valve 50 located in the chamber 36 which controls the flow of liquid refrigerant to the air cooling evaporating means 52 also located within

the chamber 36. The expansion valve 50 maintains a substantially constant pressure within the evaporating means.

An electric fan 56 connected in parallel with 5 the compressor motor 42 is provided for drawing air from the room for circulating the air over the cold surfaces of the evaporating means 52 and forcing the cooled air through the duct means into the envelope and through the porous 10 fabric wall of the envelope into the curtained enclosure where it tends to seek the bottom of the enclosure so as to provide a cool and comfortable environment for the occupant of the bed. The evaporating means 52 not only cools the air, 15 but also condenses moisture from the air and thereby dehumidifies the air. This moisture is collected in a receptacle 58. The evaporated refrigerant from the evaporating means is returned to the compressor through the suction line 60 20 which is provided with my improved suction line control valve 62 located in the compartment 36 and connected by tubing 64 to a thermostatic bulb 66 located near the air inlet of the chamber 36 so as to be responsive to room temperature. 25

The unit may be started at any time by closing the manual switch 68 which starts the operation of both the compressor motor 42 and the electric fan 56 to cool the air and to force the cooled air 30 through the porous fabric wall of the envelope into the curtained enclosure of the bed. It is, of course, necessary that the temperature of the air supplied to the bed be accurately regulated so as to provide a comfortable environment of 35 the proper temperature and humidity for the occupant of the bed. This is done entirely by my improved suction line control valve. This valve is so formed that at its normal setting, it will begin to close when the room temperature drops below approximately 95° F. It will be completely closed at approximately 82° F. room temperature. Between these two points, the amount of valve opening is and must be accurately regulated. I also provide a manually selective means 40 for raising or lowering these temperatures about 6°.

In suction line control valves, there has been considerable difficulty in providing these regulations. This is to a considerable extent due to the fact that varying pressures exist in such a valve and such varying pressures have always affected the operation of the valve and caused it to operate differently from its setting. The reason for this has been that the fluids used to control 50 a valve have been affected in a marked manner by pressure, and since these fluids were to a certain extent subject to the pressure within the suction line, the operating characteristics changed according to the pressure within the suction line.

In order to overcome this, I employ the liquid expansion of a fluid which does not change its thermal expanding characteristics to any substantial degree with a change in pressure thereof. 65 For this purpose, I use lubricating oil having a viscosity of 150 which has been dehydrated and deaerated by heat and vacuum to remove any traces of moisture and gases from the oil. Of course, other liquids such as turpentine may be used. In Fig. 2 there is shown the valve 62 having a valve body 70 with an entrance portion 72 connecting with the evaporating means 52 and an exit portion 74 connected to the suction side of the compressor. The entrance portion 72 is provided with a valve seat 76 which cooperates with

my improved form of valve needle 78 having a seat portion 80 cooperating with the valve seat 76 and a needle portion 82 within the valve orifice for measuring the flow of refrigerant through the valve when the seat portion 80 has been 5 lifted. This needle portion 82 must be accurately shaped so as to permit only a small flow when the seat has just been lifted and increasing this flow at the proper rate so as to provide the proper increases in the amount of opening according to the thermal expansion of the oil so that the temperature of the evaporating means is controlled as desired. 10

The needle valve has a reduced portion 84 beneath the needle portion 82 and a shank portion 86 which fits within a guide portion 88 in the valve body. The end of this shank is provided with a threaded portion of reduced diameter which is threaded into the end plate 90 forming the end plate of a bellows 92 sealed at its opposite end to an annular projection 94 extending from the valve guide 88. This bellows is surrounded by a heavy metal cap or cup 96 which is sealed to a rim 98 projecting from the valve guide and which receives at its closed end portion the one end of the connecting tube 64. The other end of the connecting tube 64 extends through the wall of a heavy inverted cup-shaped member 101 provided with an end plate 103 which closes its lower end. At the side opposite 30 the entrance portion of the tube 64 there is provided a charging tube 105 for charging the thermal control system with oil or other suitable fluid. 25

The cup-shaped member 101 is also provided 35 with a liquid displacement mechanism including a bellows 107 sealed at its lower end to a bellows plate 109 and the end plate 103 and sealed at its upper end to a bellows plate 111. The upper bellows plate 111 is provided with a stop pin 113 40 which is adapted to engage the closed end of the cup-shaped member 101 to limit the expansion of the bellows or the upward movement of the plate 111. This stop pin 113 is sealed to the upper end plate 111 and extends through into the 45 interior of the bellows and has a spring follower 115 threaded upon its reduced lower end portion. This spring follower 115 is held tightly against the upper flange 117 of a spring cage 119 by a fifty pound compression coil spring 121. This cage is provided with a lower flange 123 which supports the lower end of this spring. This cage at its lower end is also provided with a threaded aperture 125 which receives an adjusting screw 127, which is held in place by a shoulder which 50 engages the outer plate 129 to prevent the outward movement of the adjusting screw. 55

The spring cage 121 is held from rotation by a pair of pins 131 which engage slots 133 in the side of the cage to prevent the rotation of the cage. The head of the set screw 127 is normally provided with an indicating and manipulating device which cooperates with the dial to provide a convenient selective adjustment for controlling the temperature produced by the refrigerating system. This set screw 127 operates by moving the spring cage 119 upwardly or downwardly so as to move the upper bellows plate 111 upwardly or downwardly to displace the oil in the system and to force it to move the bellows 92 of the valve so as to move the valve to a different position. The upper bellows plate 111 of the spring cage 119 will operate together at all times excepting when the pin 113 should engage the upper wall of the cup-shaped member 101 or when 75

the bellows encounters a pressure greater than the force of the spring 121.

The bellows 92 contains refrigerant substantially at the pressure of the suction line which tends to hold the valve 16 in closed position. When the oil in the thermostatic bulb 66 is cool, there is a vacuum existing in the oil control system which permits the refrigerant pressure within the bellows 92 to hold the valve 16 tightly closed. As the oil grows warmer, it expands and exerts force upon the outside of the bellows 92 to move the valve 16 off its seat, and the higher the temperature, the greater the expansion of the oil and the wider the valve and valve needle passage is opened without being substantially affected by the refrigerant pressure within the bellows 92. Thus, I have provided a suction line control valve for the refrigerating system of a bed cooler which is not substantially affected by the pressures within the refrigerating system and which will accurately control the temperatures provided by the system to keep the atmosphere within the bed enclosure comfortable.

In Fig. 4 I have shown a domestic electric refrigerator including a cabinet 220 containing a food compartment 222 provided with a refrigerant evaporating means 224 containing ice trays 226 and provided with an adjustable switch means 228 connected by a tube 266 to a thermostatic bulb 268. The evaporating means 224 is supplied with liquid refrigerant by a liquefying apparatus including a compressor 234, driven by an electric motor 236 for withdrawing evaporated refrigerant from the evaporating means through the suction line 238, compressing the evaporated refrigerant and forwarding the compressed refrigerant to a condenser 240 where the compressed refrigerant is liquefied and collected in a receiver 242. From the receiver 242, the liquid refrigerant passes through a small capillary tube 244 which controls the flow of liquid refrigerant into the evaporating means 224. The switch 228 is connected in the electric motor circuit 246 in series with the electric motor 236 in order to control the operation of the system according to the temperature of the air within the food compartment 222.

Referring now more particularly to Fig. 5, the switch is shown with an operating bellows 248 which operates a primary lever 250 and a double toggle snap acting switch mechanism 252 which controls the opening and closing of the switch contacts 254 to control the operation of the compressor motor 236. The primary lever 250 is held in operative relation with the bellows 248 by a tension spring 256 whose tension may be controlled by a selective adjusting mechanism including a temperature control knob 258. The switch is also provided with a single cycle loading mechanism which includes a finger manipulator 260 connected to a toggle mechanism 262 provided with a roller 264 adapted to bear upon the primary lever 250 to load the bellows for a single cycle in order to raise the temperature of the evaporating means for a single cycle.

The primary bellows 248 is connected by the tube 266 to the thermostatic bulb 268 similar to the thermostatic bulb 101 in Fig. 2. This thermostatic bulb contains a bellows 270 whose extension is controlled by a set screw 272 which controls the volume in the thermostatic bulb, the connecting tube and the bellows 248. This closed system is charged through the charging tube 274. This closed system may be charged either with a

volatile fluid or with a thermally expansible liquid such as oil. In the latter case, the operating characteristics of the switch will be substantially entirely controlled by the displacement of the bellows 270. In such a case, it is desirable to provide the set screw 272 with a finger manipulator like the finger manipulator 258 and a suitable dial for indicating the selection which may be obtained by its adjustment. By the use of oil or other liquid expansible fluid in connection with such a switch, the operating characteristics may be made very accurate and may be varied within rather wide limits by properly proportioning the size of the elements in the closed system including the bellows 248, the connecting tube and the thermostatic bulb 268.

While the form of embodiment of the present invention as herein disclosed constitutes a preferred form, it is to be understood that other forms might be adopted, all coming within the scope of the claims which follow.

What is claimed is as follows:

1. Refrigerating apparatus including an evaporating means, a liquefying means for supplying liquid refrigerant to and for withdrawing evaporated refrigerant from the evaporating means, a valve for controlling the withdrawal of refrigerant from the evaporating means, a metering means in series with the valve for providing a throttling of the flow of refrigerant when the valve is open, and temperature responsive means for operating said valve and said metering means for controlling the withdrawal of refrigerant according to temperatures.

2. Refrigerating apparatus including an evaporating means, a liquefying means for supplying liquid refrigerant to and for withdrawing evaporated refrigerant from the evaporating means, a valve means for controlling the withdrawal of refrigerant from the evaporating means, a diaphragm means connected to the valve means, said diaphragm means being exposed on one side to the refrigerant controlled by the valve means, an enclosure for the other side of said diaphragm means, said enclosure containing a liquid in contact with the diaphragm means, said liquid having a boiling point sufficiently high to keep it in a liquid state below 120° F.

3. Refrigerating apparatus including an evaporating means, a liquefying means for supplying liquid refrigerant to and for withdrawing evaporated refrigerant from the evaporating means, a valve means for controlling the withdrawal of refrigerant from the evaporating means, a diaphragm means connected to the valve means, said diaphragm means being exposed on one side to the refrigerant controlled by the valve means, an enclosure for the other side of said diaphragm means, a tube connected to said enclosure, a bulb connected to said tube, said enclosure, said tube and said bulb containing a liquid having a boiling point sufficiently high to keep it in a liquid state below 120° F.

4. Refrigerating apparatus including an evaporating means, a liquefying means for supplying liquid refrigerant to and for withdrawing evaporated refrigerant from the evaporating means, a valve means for controlling the withdrawal of refrigerant from the evaporating means, a diaphragm means connected to the valve means, said diaphragm means being exposed on one side to the refrigerant controlled by the valve means, an enclosure for the other side of said diaphragm means, a tube connected to said enclosure, a bulb connected to said tube, said enclosure, said tube

- and said bulb containing a liquid having a boiling point sufficiently high to keep it in a liquid state below 120° F., and means for changing the volume of said bulb.
5. Refrigerating apparatus including an evaporating means, a liquefying means for supplying liquid refrigerant to and for withdrawing evaporated refrigerant from the evaporating means, a valve for controlling the circulation of refrigerant through the evaporating means, means forming a flexible chamber operatively connected to the valve means, said means forming a flexible chamber being located in heat conducting relationship to the refrigerant controlled by the valve means, and said flexible chamber containing a liquid having a boiling point sufficiently high to keep it in a liquid state and having a congealing point sufficiently low to keep it in a liquid state during all conditions of normal use and operation.
10. 6. Refrigerating apparatus including an evaporating means, a liquefying means for supplying liquid refrigerant to and for withdrawing evaporated refrigerant from the evaporating means, a valve means for controlling the circulation of refrigerant through the evaporating means, means forming a flexible chamber for operating the valve means, said means forming a flexible means being in heat conducting relationship with the refrigerant controlled by the valve means, a tubular means connected to said flexible chamber, said tubular means being sealed at the end opposite flexible chamber, said flexible chamber and said tubular means containing a liquid having a boiling point sufficiently high to keep it in a liquid state and having a congealing point suffi-

ciently low to keep it in a liquid state during all conditions of normal use and operation.

7. Refrigerating apparatus including an evaporating means, a liquefying means for supplying liquid refrigerant to and for withdrawing evaporated refrigerant from the evaporating means, a valve for controlling the circulation of refrigerant through the evaporating means, means forming a flexible chamber operatively connected to the valve means, said means forming a flexible chamber being located in heat conducting relationship to the refrigerant controlled by the valve means, and said flexible chamber containing a liquid having a boiling point sufficiently high to keep it in a liquid state below 120° F. and having 15 a congealing point sufficiently low to keep it in a liquid state above 0° F.

8. Refrigerating apparatus including an evaporating means, a liquefying means for supplying liquid refrigerant to and for withdrawing evaporated refrigerant from the evaporating means, a valve means for controlling the circulation of refrigerant through the evaporating means, means forming a flexible chamber for operating the valve means, said means forming a flexible means being in heat conducting relationship with the refrigerant controlled by the valve means, a tubular means connected to said flexible chamber, said tubular means being sealed at the end opposite flexible chamber, said flexible chamber and 30 said tubular means containing a liquid having a boiling point sufficiently high to keep it in a liquid state below 120° F. and having a congealing point sufficiently low to keep it in a liquid state above 0° F.

DONALD H. REEVES.
